CLAIM

The ornamental design for a wearable device, as shown and described.

DESCRIPTION

FIG. 1 is a front perspective view of a wearable device according to my new design;

FIG. 2 is rear perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a rear elevation view thereof;

FIG. 8 is a front elevation view thereof;

FIG. 9 is a top plan view showing the wearable device in an example use thereof; and,

FIG. 10 is another front perspective view thereof showing only an enlarged main body of the wearable device and without the environmental device straps shown in broken lines in FIGS. 1-9.

The broken lines shown in the drawings are for the purpose of illustrating environmental structure and form no part of the claimed design.
